TELEPHONE SWITCHBOARD

Robert E. Bearse, New York, N.Y., assignor to Western Electric Company, Incorporated, New York, N.Y., a corporation of New York

Original design application Dec. 16, 1968, Ser. No. 14,973. Divided and this application Mar. 27, 1969, Ser. No. 16,479

Term of patent 14 years

Int. Cl. D14—03

U.S. Cl. D26—14

FIG. 1

FIG. 2

FIG. 3

FIG. 1 is a perspective front, top and left side view of a telephone switchboard showing my new design; FIG. 2 is a left side elevational view thereof; and

FIG. 3 is a right side elevational view thereof.

The broken line showing of legible matter is for illustrative purposes only. The dominant features of my new design reside in the portions shown in solid lines on the drawing. The back, not shown, is unornamented.

This is a division of design application Ser. No. 14,973, filed Dec. 16, 1968.

I claim:

The ornamental design for a telephone switchboard, substantially as shown and described.
